(57) **CLAIM**

The ornamental design for an exercise apparatus, as shown and described.

DESCRIPTION

FIG. 1 is a perspective view of an exercise apparatus; FIG. 2 is a right perspective view thereof; FIG. 3 is a left perspective view thereof; FIG. 4 is a rear perspective view thereof; and, FIG. 5 is a top perspective view thereof.

The broken lines shown in the figures are for the purpose of illustrating environmental structure which form no part of the claimed design.
